UNITED STATES PATENT OFFICE.

EDMUND C. MORGAN, OF CHICAGO, ILLINOIS; OLIVE EUGENIE MORGAN EXECUTRIX
OF SAID EDMUND C. MORGAN, DECEASED.

MINING APPARATUS.

Application filed March 27, 1918. Serial No. 86,837.

To all whom it may concern:

Be it known that I, EDMUND C. MORGAN, a citizen of the United States, residing at Chicago, in the county of Cook and State 5 of Illinois, have invented certain new and useful Improvements in Mining Apparatus, of which the following is a specification.

This invention relates to apparatus for mining coal and similar material, and has 10 for its object the provision of apparatus of this character which shall be more economical and efficient in construction and operation.

The invention is exemplified in the combination and arrangement of parts shown in the accompanying drawings and described in the following specification, and it is more particularly pointed out in the appended 15 claims.

20 In the drawings:—

Fig. 1 is a sectional view through a mine chamber showing somewhat diagrammatically the apparatus forming the present invention in operating position.

25 Fig. 2 is a top plan view of the apparatus shown in Fig. 1.

Fig. 3 is a front elevation of a mining machine forming a part of the present invention.

30 Fig. 4 is a top plan view of the machine shown in Fig. 3.

Fig. 5 is a modified form of deflector used in connection with the machine shown in Figs. 3 and 4.

35 Fig. 6 is an elevational view of the side of the machine opposite that shown in Fig. 3.

Fig. 7 is a section substantially on line 7—7 of Fig. 4.

Fig. 8 is a section on line 8—8 of Fig. 7.

40 Fig. 9 is a section substantially on line 9—9 of Fig. 4, but with the parts in the rear of the section plane omitted.

Fig. 10 is a front elevation of the machine shown in Fig. 3.

45 Fig. 11 is a bottom plan view with part broken away of a conveyor forming a part of the present invention.

Fig. 12 is a side elevation of the conveyor shown in Fig. 11.

50 Fig. 13 is a detail of the conveyor shown in Figs. 11 and 12.

Fig. 14 is a section on line 14—14 of Fig. 9.

Fig. 15 is an elevation of a ram forming a part of the present invention. 55

Fig. 16 is a top plan view of the device shown in Fig. 15.

Fig. 17 is a plan view of a modified form of mining machine; and,

Fig. 18 is an elevation of the machine 60 shown in Fig. 17.

The apparatus constituting the present invention is especially adapted for use in connection with the system of mining indicated in Figs. 1 and 2. In the operation of this 65 method of mining, entries *a* and *b* are driven through a vein of material *c*, the entries extending for long distances in the mine. The entries *a* and *b* are spaced apart a considerable distance so that a large pillar of material 70

c is left between each pair of entries. A conveyor *d* is placed at one of the entries *a* or *b* for carrying away the material as it is mined. This conveyor may be made of a length to reach to the mine shaft, or it may 75

be made to discharge into a car mounted on a track. A second conveyor *e* is placed at right angles to the conveyor *d* in position to discharge into that conveyor. The conveyor *e* is placed adjacent the wall of the 80

pillar *c* which is being worked and is supported on horizontally extending arms or base plates *f* of a series of mine props *g*. The roof of the mine chamber above the conveyor *e* is supported by a sliding arm *h*, 85

(Figs. 7 and 8) on the head *i* of the prop *g*. The sliding arm *h* is supported on tapered ribs *j* forming a fulcrum near the center of the arm to permit the arm to automatically 90

adjust itself to unevenness in the roof of the mine. A downwardly extending hook *k* is carried at the rear of the arm *h* to prevent the arm from being slid too far forwardly and to hold it from tipping down- 95

wardly at its forward end. The prop *g* is provided with a screw threaded standard *m* for adjusting the head of the prop against the roof of the mine. The mining machine *M* (Figs. 1 and 2) is drawn along the face 100 of the vein *c* and severs a section of material therefrom, in a manner to be described, for each passage of the machine to the right,

as viewed in these figures along the face of the vein. As the material is severed from the vein it is discharged onto the conveyor *e* and from thence to the conveyor *d* which carries it away from the mining position. The mining machine *M* is moved along the face of the vein by cables *p* and *q* attached to stakes *r* located at opposite ends of the movement of the machine. The conveyor *e* is drawn forwardly after each cut made by the mining machine by means of cables *s* and *t* having their ends secured at any desired position in the entries *a* and *b*.

In my co-pending application, Serial No. 15 587,555, filed September 11, 1922, for an improvement in systems of mining, as a division of Serial No. 415,276, originally filed January 14, 1916, I have described and claimed the system of mining comprising 20 a series of roof supports, such as those illustrated at *g* in Fig. 2 having extended arms, such as those illustrated in Fig. 7 for supporting an endless conveyor in position to receive material dislodged by a mining machine operating along a mine wall extending parallel to the series of roof props and parallel to the conveyors.

The construction of the conveyor will best be understood by reference to Figs. 8, 11, 30 12 and 13. The conveyor comprises a trough 21, provided with a conveyor bed 22, over which an endless conveyor 23 travels. The trough 21 is made in sections secured together by fish plates 24, as shown in Fig. 35 13, in order that the conveyor may be taken apart to assist in placing it in position in the mine chamber. At the discharging end of the conveyor, the trough 21 is inclined upwardly, as shown in Fig. 12, and is provided with a sprocket wheel 25 for driving the endless conveyor. The sprocket wheel 25 is rotated by means of a chain 26 driven by a motor 27 mounted on a base plate 28 forming a continuation of the horizontal 40 portion of the conveyor trough. The motor 27 is geared to a shaft 29 which drives the sprocket chain 26, and said shaft 29 is geared to a shaft 30 having a pair of drums 31 and 32 mounted thereon. The drums 31 and 32 are controlled by clutches 33 and 34 respectively provided with operating handles 35 and 36. The drum 32 has the cable *t* wound thereon, and the drum 31 has the cable *s* wound upon it. The 45 cable *t* passes over a pulley 37 which directs it into the entry *a*. The cable *s* passes over suitable leaders 38 and 39 to the pulley 40 secured to the conveyor *e* at the end opposite the end on which is located the motor 27. It will be apparent that the motor end of the conveyor will be drawn forwardly by the cable *t* when the drum 32 is operated to wind in the cable. The opposite end of the conveyor is moved forwardly by operation 50 of the drum 31.

The mining machine proper is provided with a frame having a base plate 41 which rests upon the floor of the mine chamber, as shown in Fig. 7, and which carries the other portions of the mining machine. 70 Mounted on top of the base plate 41 is a deflector or guide for the severed material having a forward deflector plate 42 and a rear deflector plate 43. The outwardly turned portions of these plates, as shown 75 in Figs. 3 and 4, are connected at the lower edges by a slightly inwardly inclined base plate 44. The plates 42, 43 and 44 constitute a trough or guideway for directing the severed material laterally onto the conveyor 23, as indicated in the figures referred to. As the machine is drawn forwardly or to the right, in Fig. 2, material constantly enters the forward end of this guideway pushing the material already on the guideway outwardly through the opening at the side of the guideway above the conveyor 23.

The material is severed from the mine wall by a plurality of chain cutters arranged to sever a continuous section from the vein 90 as the machine is moved along the face thereof. The cutters for forming the severing kerfs at the top and bottom of the section extend inwardly in a horizontal direction from the face of the vein at or near the top and bottom of the vein, as indicated in Figs. 7, 9 and 10. As shown in Fig. 3, the guide plate 42 is provided at its forward edge with an upright offset slide bar 45 which has rigidly secured thereto a second slide bar 46. The two bars 45 and 46 constitute a slideway on which is mounted a slide block 47 having a horizontally extending arm 48 secured thereto, (Fig. 9). A similar block 49 is mounted for sliding movement between the bars 45 and 46 at the lower end thereof and carries a horizontally extending arm 50. The slide block 47 has secured thereto a threaded rod 51 meshing with a threaded sleeve 52 carried by brackets 53 and 54 spanning the space between the two slide bars 45 and 46, (see also Fig. 14). The sleeve 52 is provided with a worm wheel 55 operated by a worm 56 and a hand wheel 57. By this construction the slide block 47 and arm 48 may be adjusted vertically along the slide bars 45 and 46. In a similar manner the lower slide block 49 is provided with a rod 58 co-operating with a worm wheel 59 by means of 110 which the arm 50 may be given a vertical adjustment. The arm 48 is provided with an extension member 60 at the outer end thereof, shown best in Figs. 4 and 9. The extension member 60 has bifurcations 61 115 slidably mounted on the end of the arm 48, and a threaded rod 62 is arranged to adjust the member 60 relative to the arm 48. A chain guide 63 extends along the sides of the arm 48 and around the end 120 125 130

of the extension member 60, and a cutter chain 64 is mounted for sliding movement along the guideway 63. The cutter chain is driven by a sprocket wheel 65 secured to the upper end of a drive-shaft 66. The sprocket wheel 65, as shown in Fig. 9, is mounted for rotation in a bearing 67 carried on the slide block 47. The lower end of the shaft 66 has a squared portion 68 fitting a similarly shaped opening in a sleeve 69 mounted for rotation in a bearing 70 carried by the brackets 54 and 71. It will be clear that the shaft 66 is free to move up and down when the slide block 47 is adjusted in the slideways 45 and 46 without disturbing the driving connection between the shaft and the sleeve 69. The sleeve 69 is provided with a worm wheel 72 meshing with a worm 73 mounted on a shaft 74. The lower end of the sleeve 69 engages the squared portion 75 of a shaft 76 which carries a sprocket wheel 77 at its lower end. The sprocket wheel 77 drives a cutter chain 78 which travels on the arm 50 in a manner similar to that of the chain 64 on the arm 48. The arm 50 also carries an extension 79 at its outer end provided with an adjusting screw 80. The shaft 74 is driven by a motor 81 mounted on a shelf 82 secured to the guard plate 42, as shown in Fig. 3.

Guard flanges 83 and 84 are arranged to protect the cutter chains as they pass around the sprocket wheels 65 and 77 respectively. An upright plate 85 is positioned in front of the mechanism just described and is provided with an opening 86 through which the cable *q* passes, as shown in Figs. 3, 4 and 10. The inner end of the cable *q* is wound upon a drum 87 driven through gearing 88 by a motor 89 mounted on the plate 90 secured to the base plate 41 and formed integral with the guard plate 42, as shown in Fig. 3. It will be seen that when the motor 89 is operated to wind the cable *q* on the drum 87, the machine will be moved in a forward direction. It should be noted also, as shown in Fig. 4, that the operating motor 81 and the associated mechanism and also the motor 89 are protected by the guard plate 42 from the material passing from its severed position to the conveyor.

Secured to the lower edge of the rear guard plate 43 and extending laterally and inwardly therefrom, is a platform 91 which may be formed integral with the guard plate 43 and which rests upon the base plate 41, as shown in Fig. 6. This platform is provided with a motor base 92 which carries motors 93 and 94. Secured to the forward portion of the platform 91 and guard plate 43 is a supporting frame 95, (Figs. 6 and 7). This supporting frame 95 is offset, as shown in Fig. 7, to bring the outer surface substantially in a plane with the edge of the base plate 41.

This offset portion is provided with a chain guide 96 along which a cutter chain 97 is mounted to travel. The guide is held in place by a plate 98 secured to the frame 95 by screws 99. The forward portion of the frame 95 is also provided with a chain guide 100 held in place by a plate 101. An adjustable yoke 102 having downwardly extending legs 103 and 104 is carried on the upper portion of the frame 95. The leg 103 is secured to the frame by screws 105 and is supported by a block 106 also fastened to the frame by screws 107. The leg 104 is held in place by the plate 101 and is provided with an adjustable plate 108 which rests upon the upper end of the plate 101. The supporting block may be held in position beneath the end of the leg 104 by means of screws 109. The yoke 102 may be adjusted vertically by the threaded rods 110 and secured in adjusted position by the blocks 106 and 108 and the co-operating screws. The yoke 102 is provided with a chain guide 111 extending around its forward and upper edges. In this way an adjustable upright frame is provided for supporting the cutter chain 97 in position to form a kerf in the material to be mined in a plane offset inwardly from the face of the mine vein. The forward portion 112 of the plate 43 is carried within the loop formed by the chain 97 and has its forward edge 113 positioned in the cutting plane of the chain. By this arrangement the deflector plate 43 is enabled to slide in behind the section of material severed by the cutter chain and to force the material outwardly away from the mine wall and thus provide clearance space for the motors 93 and 94. The cutter chains 64, 78 and 97 are positioned to form a core-cutter, as shown in Fig. 10, so that as the machine is fed forwardly by the winding of the cable *q* on the drum 87, the chains form a closed cut in the mine wall surrounding a body of material and extending continuously along the wall in the direction of movement of the machine. In this way a continuous core section is completely severed from the mine wall and forced outwardly away from the wall onto the conveyor arranged adjacent the path of movement of the machine. The cutter chain 97 is driven by a sprocket wheel 115 (Fig. 6) carried on a shaft 116 mounted in bearings 117 (Fig. 4) on a pedestal 118 supported on the motor base 92. The shaft 116 is driven by a worm gear connection from the motor 93. The motor 94 is connected by spur gears with the drum 120 on which the cable *p* is wound for drawing the machine backwardly into a position to begin a new cut after each cut is completed.

As will be seen from Fig. 4 of the drawing, the forward runs of the cutter chains 130

- are positioned substantially in the same plane at the front end of the mining machine. This arrangement of the cutting portions of the cutter chains is important because of the fact that it completely severs the core of material that is being disconnected from the mine wall, on all sides of the core at the point where the core begins to enter the machine. The only point of attachment between the core and the wall that is not broken is at the front end of the core. As the machine moves forwardly, the portion of material being disconnected projects through the loop formed by the cutters until it contacts with the deflector plate 43, which forces the material to one side and breaks it from its connection with the mine wall at its forward end. Because of the fact that the cutting is done at the very front portion of the machine, the leverage given the deflector plate 43 is greater than would be the case if the cutters were set farther back on the machine frame. This permits the machine to be made comparatively short as it is not necessary to provide extra length in the machine frame to supply the necessary leverage for breaking the coal from its connection with the mine wall. It should be noted that not only the upper and lower cutters operate at the front portion of the machine, but all three of the cutters have their severing portions located in substantially the same plane at the front of the machine.
- In order that the entry at the side of the portion of the vein being worked from which the successive cuts are started may be free to receive the machine in position to start a cut, the conveyor which carries the material toward the mine shaft must be positioned in the entry toward which the machine moves in making the cuts. It follows from this that the conveyor section E must be driven in the same direction in which the mining machine is moved and must be positioned far enough away from the face of the vein to carry the material past the mechanism for driving the horizontal cutters and yet leave space for this mechanism between the conveyor and the face of the vein. In order that the conveyor may be thus spaced away from the face of the vein, the deflector is made to extend a sufficient distance laterally, not only to carry the severed material out of its native position, but to move it past the rear of the driving mechanism and discharge it on the conveyor at a point beyond the outermost portion of the cutting mechanism.
- As shown in Fig. 5, the deflector plate 43' instead of being curved away from the vertical, as shown in Fig. 4, may stand straight up and down and be curved in a horizontal direction only. The plate also may be pivoted, as indicated at 121, and

provided with a pitman 122 for reciprocating the plate to assist in the movement of the material toward the conveyor. In the form shown in Fig. 5, the pitman 122 is operated by a crank 123 carried by a worm gear 124 driven by a shaft 125. The shaft 125 may be operated in any suitable manner, as by connection with the motor 93.

As the machine is being moved to sever a section of material from the mine wall, the severed section or core passes through the space bounded by the cutters and forces the material already severed against the deflector plate 43 which breaks the material and forces it outwardly onto the conveyor. When the machine reaches the end of a cut however, there is no longer any pressure on the severed material to force it from the machine onto the conveyor. The material may be carried backwardly with the machine however, and when the machine is positioned to begin a new cut, the material thus brought back will be forced from the machine as the new cut is begun. To prevent the material falling from the forward end of the machine during this backward movement, a hinged door 126, (Figs. 3, 4 and 10), is pivoted at 127 to the plate 85 at the forward end of the machine. As shown in Fig. 10, this door may be swung into position to close the core space formed by the cutters 64, 78 and 97. A latch 128 is provided for holding the door in closed position, and when thus closed, the machine may be moved backwardly without danger of the severed material falling from the front end of the machine. It will be seen that during this backward movement, a portion of the severed material will rest upon the cutter arm 50, and in order to prevent this arm from dragging on the ground, it may be adjusted upwardly by means of the threaded rod 58.

In order to avoid the necessity of carrying the material remaining on the machine at the end of a cut backwardly with the machine to its new position, a ram may be provided, as shown in Figs. 2, 15 and 16, for forcing the material from the machine after the completion of each cut. This ram, as shown in Fig. 15, is provided with a horizontally movable rack 140, driven by a pinion 141, operated by a motor 142, through gearing 143. The ram is mounted on a base plate 144, preferably made integral with or rigidly attached to the base plate 28 of the conveyor mechanism, so that the ram and conveyor may all be moved forwardly by the same operation after the completion of each cut. A threaded rod 145 is carried in a standard 146 on the upper portion of the ram support, and is provided with a hand wheel 147 for forcing the upper end of the rod 145 into contact with the roof of the mine for holding the ram in position. The

forward end of the rack 140 carries a head 148 for contacting with the severed material to force the material through the core formed by the chain cutters and from the mining machine onto the conveyor.

In the form of the mining machine shown in Figs. 17 and 18, the base plate 41 is omitted and the platform plates 90 and 91 are permitted to rest directly upon the floor of the mine. This construction leaves a space 150 just back of the cutter arms 48 and 50 vacant, so that the coal as it is severed passes through the core space formed by the cutter chains, and when it becomes detached 15 is permitted to rest directly upon the floor of the mine chamber. As the machine is moved forwardly however, the deflector plate 43 forces the coal over the base plate 41 onto the conveyor in a manner similar to 20 that of the operation of the machine previously described. In other respects the machine shown in Figs. 17 and 18, is similar to that of the other form.

I claim:—

25 1. In a system of mining, the combination with a mining machine frame, of kerf-cutting mechanism mounted thereon, means for operating said kerf cutting mechanism including rectilinear movement of said mining 30 machine frame to effect the feeding of said cutting mechanism along a mine wall, an elongated conveyor comprising a conveyor frame, an endless conveyer extending longitudinally thereof to occupy a position 35 adjacent the path of travel of said mining machine frame and substantially parallel to such path of travel in position to receive material from the mining machine throughout the feeding path of travel thereof, and 40 upright curved deflecting means on said mining machine frame for directing the dislodged material from said mining machine onto said endless conveyer as said mining machine travels along the side of said conveyer.

45 2. In a system of mining, the combination with a mining machine frame, of kerf cutting mechanism extending in advance of said frame relatively to the feeding path of travel thereof in position to cut spaced-apart horizontal kerfs and an upright connecting kerf spaced back from the face of the mine wall, each of said kerfs being in advance of said frame, means for operating said kerf cutting mechanism including rectilinear feed of said frame along the face of a mine wall to cut a column of material extending onto said frame, a conveyer having a stationary frame occupying a position adjacent the path of travel of said mining machine frame, said conveyer also comprising an endless conveyer on said conveyer frame in position to travel parallel to the path of travel of said mining machine frame, and 60 means on said mining machine frame for de-

flecting cut material onto said endless conveyer continuously during the feeding movement of said kerf cutting mechanism.

3. In a system of mining, the combination with a supporting frame, of kerf-cutting mechanism mounted thereon for cutting a single column of material from an upright face of a mine wall to project from said kerf-cutting mechanism onto said frame, means for operating said kerf-cutting mechanism including rectilinear feed of said frame, a deflector mounted on said frame for directing the cut material from said frame, and a conveyor extending along the path of travel of said frame for continuously receiving directly from said deflector the dislodged material during the operation of said kerf-cutting mechanism.

4. In a system of mining, the combination with a supporting frame, of two spaced-apart kerf-cutters mounted on said frame in position to cut substantially horizontal spaced-apart kerfs, said kerf-cutters being also mounted on said frame to have an unobstructed space between them for the passage of the cut material onto said frame, an additional kerf-cutter mounted on said frame to cut an upright kerf spaced back from the face of the mine wall and connecting the inner ends of the horizontal kerfs to complete the cutting of a single column of material extending through said unobstructed space onto said frame, means for operating said kerf-cutters including bodily rectilinear movement of said frame to secure feeding movement of said kerf-cutters, a conveyor mounted adjacent the path of travel of said frame, and means for transferring the cut material automatically from its native position along said frame directly onto said conveyor.

5. In a system of mining, the combination with a supporting frame, of a plurality of kerf-cutters mounted on said frame to form a loop having an unobstructed core-opening therethrough, means for operating said cutters to cut a single core of material extending through such unobstructed core-opening, a conveyer adjacent the path of travel of said frame, and a deflector mounted on said frame for transferring the cut material directly onto said conveyer.

6. In a system of mining, the combination with a plurality of endless chain kerf-cutters, of a frame for supporting said kerf-cutters to form a closed loop having an unobstructed core-opening therethrough, means for operating said kerf-cutters including rectilinear feed thereof by bodily rectilinear movement of said frame, a conveyer mounted adjacent the path of travel of said frame and substantially parallel to the face of the mine wall at a distance therefrom approximately equal to the width of said frame, and mechanism on said frame for engaging the cut ma-

- terial and breaking it and transferring it directly from said frame onto said conveyer.
7. In a system of mining, the combination with a supporting frame, of core-cutting mechanism mounted on said frame, means for operating said core-cutting mechanism including the feed thereof by rectilinear movement of said frame along the mine wall, a conveyer, means for positioning said conveyer adjacent the path of feeding movement of said frame, and means for directing the cut material from said core-cutting mechanism over said frame onto said conveyer.
8. In a mining machine, the combination with core-cutting mechanism comprising means for cutting a kerf in a substantially horizontal plane at the floor of a mine chamber, and means for cutting a kerf in a substantially horizontal plane at the roof of such mine chamber, of means for independently adjusting the floor kerf-cutting means and the roof kerf-cutting means to vary the elevation of either the floor kerf or the roof kerf independently of the elevation of the other, and means for operating said core-cutting mechanism including the feed thereof.
9. In a mining machine, the combination with a plurality of plane kerf-cutters each comprising a traveling chain cutter, of means for supporting two of said plane kerf-cutters in spaced-apart position with an unobstructed core space between them, and means for supporting a third plane kerf-cutter in a plane extending transversely of the planes of said spaced-apart kerf-cutters and in a plane spaced-back from the face of the mine wall and approximately parallel thereto.
- 40 10. In a mining machine, the combination with a supporting frame, of spaced-apart plane kerf cutters mounted on the forward portion of said supporting frame to extend transversely thereof, relative to the path of travel of said supporting frame, each of said kerf cutters comprising a traveling cutter chain, means for driving said cutter chains, and means for propelling said supporting frame to effect feeding movement of said plane kerf cutters in a direction extending transversely of the kerf cutters and longitudinally of said frame to cut material to extend onto said frame.
11. In a mining machine, the combination with a supporting frame, of cone-cutting mechanism carried by the forward portion of said frame and comprising a plurality of spaced-apart elongated chain kerf-cutters extending transversely of the path of travel of said supporting frame, and means for operating said core-cutting mechanism including bodily feeding movement of said frame and said chain kerf-cutters along the face of a mine vein in a direction transversely of said chain kerf-cutters.
12. In a mining machine, the combination with a supporting frame, of a chute carried by said frame, mechanism mounted on said frame for cutting a single core of material to extend along said chute, and means for operating said cutting mechanism including rectilinear movement of said frame along the mine wall to effect feeding movement of said cutting mechanism and the movement of said chute along under the single core of material cut.
13. In a mining machine, the combination with a supporting frame, of an upright plane kerf-cutter extending along the inner side of said frame to the forward portion thereof, a plurality of spaced-apart elongated kerf-cutters extending from the outer side of said frame to the inner side thereof at the forward portion of said frame to form with said first-named kerf-cutter a loop for making a substantially continuous kerf in the material to be mined, the space between said elongated cutters being free and unobstructed for the passage of cut material between them, and means for moving said supporting frame together with said kerf-cutters to form a loop-shaped kerf in a mine wall extending continuously therewith.
14. In a mining machine, the combination with a supporting frame, of a pair of spaced-apart chain kerf-cutters, means for holding said pair of cutters in position to extend across the forward portion of said frame, a third chain kerf-cutter, means for supporting said third cutter in position to form an upright kerf substantially connecting the inner ends of the kerfs formed by said first-mentioned cutters, means for actuating said kerf-cutters, and means for propelling said frame to effect bodily feeding movement of said kerf-cutters during the actuation thereof to cut a column of material along the mine wall extending through the free and unobstructed space between said pair of kerf-cutters and in front of the upright connecting kerf-cutter.
15. In a mining machine, the combination with a supporting frame, of a chain kerf-cutter mounted on said frame and extending along the inner side thereof in position to cut an upright kerf in a mine wall at the forward inner side of said frame, means for actuating said chain kerf-cutter, means for propelling said supporting frame along the mine wall to secure bodily feeding movement of said kerf-cutter during the actuation thereof, and a deflector extending from the forward portion of said frame adjacent said kerf-cutter to the outer side of said frame at the rear portion thereof for directing cut material along said frame and off the same.
16. In a mining machine, the combination with an elongated supporting frame, of an upright chain kerf-cutter mounted at the

inner side of said frame and extending to the forward end of said frame, means mounted on the inner side and rear portion of said frame for operating said upright chain kerf-cutter including the feed thereof by rectilinear movement of said frame parallel to its length to form a kerf substantially parallel to the face of the mine wall and offset inwardly from said face, and means for directing the cut material from the forward portion of said cutter along said frame in front of the said operating means to the outer side of said frame.

17. In a mining machine, the combination with a supporting frame having a forward end relative to its feeding path of travel, of an elongated chain kerf cutter mounted on said frame and in its entirety extending transversely across such forward end of said frame, a curved deflector chute extending rearwardly from said forward end and means mounted on the forward outer portion of said frame for driving said kerf cutter and for feeding the same by movement of said frame along the mine wall with the entire kerf cutter at such forward end.

18. In a mining machine, the combination with a supporting frame, of an elongated chain kerf cutter comprising an elongated cutter bar extending across the forward end of said frame with the cutter chain in its entirety also at such forward end in position to cut an under kerf substantially at the level of the mine floor, means mounted at the forward outer portion of said frame for operating said undercutter, including feeding movement thereof while said undercutter as a whole remains in such transverse position at the forward end of said frame, and a chute comprising upright spaced-apart curved walls extending rearwardly from said cutter.

19. In a mining machine, the combination with a supporting frame, of an upright chain kerf-cutter mounted on said frame and extending along the inner side thereof to the forward end of said frame, a plurality of spaced-apart elongated chain kerf-cutters mounted at the forward portion of said frame and extending transversely thereof to said upright kerf-cutter, means for actuating said kerf-cutters, and means for moving said frame along a mine wall to effect bodily feeding movement of said cutters during the actuation thereof to cut a kerf spaced back from the face of the mine wall and substantially parallel thereto, and a plurality of horizontal spaced-apart kerfs connecting the upright kerf.

20. In a mining machine, the combination with a supporting frame adapted to slide along the floor of a mine chamber adjacent an upright mine wall and comprising a platform having a forward scooping edge, of

core-cutting mechanism mounted adjacent said scooping edge, means for actuating said core-cutting mechanism, and means for sliding said frame along the floor during the actuation of said core-cutting mechanism to cause the said edge to scoop the cut material.

21. In a mining machine, the combination with a supporting frame, of a chain kerf-cutter mounted on the inner side of said frame to cut a kerf along a mine wall substantially from the floor to the roof thereof and in a plane substantially parallel with the face of the mine wall, spaced-apart elongated chain kerf-cutters at the forward portion of said frame one for cutting kerfs substantially at the floor of the mine chamber and the other for cutting a kerf substantially at the roof of the mine chamber, said kerfs connecting with the upright kerf, means for actuating said kerf-cutters, and means for moving said frame along the mine wall to secure rectilinear feeding movement of said kerf-cutters during the actuation thereof.

22. In combination, a mining machine having a relatively thin base plate, a cutter in position to form a kerf in a mine wall into which kerf said base plate is moved, an upright cutter supported at the inner edge of said base plate for forming a kerf along a plane spaced inwardly from the face of said mine wall, and a third cutter mounted to cut a kerf extending to the upper edge of the upright cutter and spaced above the first-named cutter to leave the space above the latter free and unobstructed over the entire height of the upright cutter.

23. In combination, a mining machine having a base plate, a cutter arranged to form a kerf extending inwardly from the face of a mine wall into which kerf said base plate may be moved, a second cutter carried by said base plate at the inner edge thereof for forming a kerf in a plane offset inwardly from the face of said mine wall to sever a section of material from said wall, and a third cutter for disconnecting the material so severed at the upper portion thereof, the space bounded by said three cutters being free and unobstructed.

24. In a mining machine, the combination with a supporting frame having a base plate provided with a receiving lip at the floor of the mine chamber, of an elongated chain kerf-cutter located in advance of the said receiving lip and approximately in a plane extending through said receiving lip, a second chain kerf-cutter located at the inner edge of said base plate in position to form an upright kerf spaced back from the face of the mine wall, means for operating said chain kerf-cutters to cut connecting kerfs in intersecting planes and move said base plate under the cut material while the space above said base plate remains free and un-

obstructed for the passage of cut material over substantially the entire height of the kerf cut by the inner kerf-cutter, and spaced apart upright walls on said base frame extending rearwardly from the ends of said receiving lip.

25. In combination, a mining machine having a base plate, a cutter for forming a kerf in which said plate may be moved, a second cutter positioned at the inner edge of said plate for forming a kerf effect inwardly from the face of the mine wall, and an upright curved deflecting plate mounted on said base plate and extending diagonally across the latter from the inner forward edge to the rear outer edge to not only wedge the cut material from the unmined mass but also deflect it from the mine wall a distance equal approximately to the width of said base plate.

26. In a mining machine, the combination with a supporting frame, of a chute having a forward receiving edge at the floor of the mine chamber with a space above said chute free and unobstructed up to the roof of the mine chamber, core-cutting mechanism extending from the forward portion of said frame and associated with the said receiving edge to cut a column of material extending into such free and obstructed space and into said chute, and means for operating said core-cutting mechanism including rectilinear movement of said supporting frame and the movement of said receiving edge under the cut material to cause the latter to extend along said chute.

27. In a mining machine, the combination with a chain kerf cutter, a support for holding said kerf cutter in position for permitting said support to be moved into the kerf formed by said kerf cutter and extend along such kerf back of the kerf cutter, a curved deflecting chute comprising spaced-apart curved walls one being an upright guard plate mounted on said support and extending from one side thereof toward the other side thereof transversely of the path of travel of said kerf cutter and of said support, and a chain kerf cutter supported by said guard plate in position to cut a kerf in a plane offset inwardly from the face of the mine wall.

28. In combination, a mining machine having a base member, a cutter for forming a kerf in which said base member may be moved, a guard plate carried by said base member, a cutter chain supported by said guard plate in position to form a kerf offset inwardly from the face of a mine wall, and means for operating said cutter chain located in position to be protected by said guard plate.

29. In a mining machine, means for forming a plurality of kerfs extending inwardly from the face of a mine wall, means for

forming a kerf spaced inwardly from said mine wall connecting said first mentioned kerfs thus severing a section of material from said mine wall within the space bounded by said kerfs, and means for moving the material thus severed away from said mine wall to provide space for the operating mechanism of said last mentioned kerf forming means.

30. In combination, a plurality of chain cutters arranged to form kerfs extending inwardly from the face of a mine wall, another chain cutter arranged to form a kerf positioned inwardly from the face of said wall in a plane intersecting the planes of said first mentioned kerfs thus severing a section of material from said mine wall, operating mechanisms for said kerf cutters and means for moving the material thus severed away from its native position to provide space for the operating mechanism of said second mentioned chain cutter.

31. In a mining machine, a plurality of chain cutters arranged to form kerfs extending inwardly from the face of a mine wall, another chain cutter, means for supporting said last mentioned cutter in a position to form a kerf spaced inwardly from the face of said wall and intersecting the kerfs formed by said first mentioned cutters, operating means for said last mentioned chain cutter, and a guard plate arranged to protect a portion of said cutter and said operating means and to direct material from the space bounded by said cutters.

32. In a mining machine, a base plate, a chain cutter for forming a kerf extending inwardly from the face of a mine wall and in which said base plate is movable, a second chain cutter carried by said base plate at the inner edge thereof in position to form a kerf spaced inwardly from the face of said mine wall to sever a section of material therefrom, a guard plate carried by said base plate and arranged to support said cutter and to move the material severed thereby away from said mine wall, and operating means for said cutter and protected by said guard plate from the material severed thereby.

33. In combination, a mining machine frame, a pair of chain cutters extending laterally from said frame in position to form kerfs extending inwardly from the face of a mine wall, another chain cutter carried by said mining machine frame and arranged to form a kerf spaced inwardly from the face of said wall, operating means for said cutter, and a guard plate arranged to support said other cutter and to move the material severed thereby away from said mine wall and out of the way of said operating means.

34. In a mining machine, the combination

with a supporting frame, of kerf-cutting mechanism mounted thereon, and a deflector plate extending rearwardly and diagonally and arcuately and being curved upwardly 5 to form an overhanging deflecting portion.

35. In a mining machine, an endless cutter chain, means for supporting said cutter chain in a position to form a kerf spaced inwardly from the face of a mine wall, operating means for said cutter chain, and a plate having its forward end positioned behind the forward run of said cutter chain and in the cutting plane thereof and having its rear portion curved outwardly to direct the material severed by said cutter chain away from said mine wall to form clearance space for said operating mechanism.

36. In combination, a mining machine frame, an upright chain cutter carried by said frame at one edge thereof, a motor mounted on said frame for driving said cutter, and a deflector carried by said frame for moving the material severed by said cutter to form clearance space for said motor and to guard the latter.

37. In combination, a mining machine frame, an upright deflector carried by said frame, a chain cutter carried by said deflector and having its forward run positioned in front of the forward end of said deflector, and a motor carried by said frame and positioned behind the rear portion of said deflector.

38. In combination, a mining machine frame, an upright deflector carried by said frame, an upright chain cutter supported at the forward end of said frame, and an adjustable frame work for said cutter.

39. In combination, a mining machine frame, a chain cutter carried at the forward end of said frame and operating in an upright plane, a deflector carried by said frame and having its forward edge positioned in the rear of the forward run of said cutter and in the cutting plane thereof and having its rear portion curved away from the plane of said cutter to direct the material severed, and operating means for said cutter positioned in the clearance space provided behind said deflector.

40. In combination, a mining machine frame, a chain cutter carried by said frame in an upright position at one edge thereof, chain cutters extending across the forward portion of said frame, operating means for said chain cutters, and guard plates for directing towards loading position the material severed by said chain cutters and for protecting said operating means from said material.

41. In combination, a mining machine frame, a cutter carried at one edge of said frame in position to form a kerf spaced inwardly from the face of a mine wall, cut-

ters carried at the forward portion of said frame for forming kerfs extending inwardly from the face of said wall respectively to the upper and lower extremities of said inwardly spaced kerf, means for driving said last mentioned cutters, and a guard plate positioned for protecting said driving means from the material severed by said cutters.

42. In combination, a mining machine frame, a cutter positioned at one edge of said frame for forming an upright kerf spaced inwardly from the face of a mine wall, cutters positioned at the forward portion of said frame for forming kerfs extending inwardly from the face of said wall to said first mentioned kerf, operating means for said first mentioned cutter, a deflector plate for moving the material severed by said cutter to form a clearance space for said operating means, operating means for said second mentioned cutters, and a guard plate for protecting said last mentioned operating means from said material.

43. In a mining machine, the combination with a supporting frame, of transverse spaced-apart elongated chain kerf-cutters mounted on said frame in position to undercut and over-cut a section of material extending along the face of the mine vein, each of said kerf-cutters comprising an elongated cutter frame rigidly connected to said supporting frame, and means for independently adjusting the distance of each of said cutters from the other cutter and thereby independently adjust the elevation of each of said cutters.

44. In a mining machine, the combination with a supporting frame, of an upright chain kerf-cutter mounted at the inner edge of said frame in an upright plane in fixed relation to said frame to cut an upright kerf at the rear of a section of material extending along the face of the mine vein, spaced-apart chain kerf-cutters each comprising a cutter frame rigidly connected to said supporting frame to prevent swinging thereof relatively to said supporting frame, means for operating said chain kerf-cutters to cut a kerf at the floor of the mine chamber and a kerf at the roof thereof and an upright kerf spaced back from the face of the mine wall, and means for adjusting the distance between the floor kerf-cutter and the roof kerf-cutter.

45. In a mining machine, the combination with a mining machine frame, of a guard plate, a pair of laterally projecting chain cutters adjustably mounted on said guard plate, means for operating said cutters, and means for supporting said guard plate to protect said operating means from dislodged material.

46. In a mining machine, the combination with a mining machine frame, of an

upright guard plate on said frame, laterally projecting arms mounted on said guard plate, chain cutters carried by said arms, means for operating said chain cutters, and 5 means for supporting said guard plate to protect said operating means against dislodged material.

47. In a mining machine, the combination 10 with a supporting frame, of a cutter carried by said frame in position to form an upright kerf, additional spaced-apart kerf-cutters carried by said frame in position to form spaced-apart kerfs in planes intersecting said upright kerf, each of said additional kerf-cutters comprising a cutter frame rigidly connected to said supporting frame to prevent swinging movement thereof relatively to said supporting frame, and means for independently adjusting the distance of each of said additional kerf-cutters from the other additional kerf-cutter.

48. In a mining machine, the combination 15 with a supporting frame, of a kerf cutter mounted thereon in position to cut an upright kerf, spaced-apart kerf cutters mounted on the forward portion of said frame in position to cut spaced-apart kerfs in planes intersecting the plane of said upright kerf approximately at the upper and lower 20 limits of said upright kerf cutter, means for operating said spaced-apart kerf cutters and said upright kerf cutter including movement of said frame to secure feeding of all 25 of said kerf cutters to form a core extending through the unobstructed core space between said spaced-apart kerf cutters in front of said upright kerf cutter, and spaced-apart 30 guard plates in position on said supporting frame to protect the said operating means 35 against dislodged material and to form a chute for the passage of core material from said core space over said supporting frame.

49. In a mining machine, the combination 40 with a supporting frame, of a transversely extending plane kerf-cutter comprising an 45 elongated cutter frame, a bracket for carrying said cutter-frame, means on said supporting frame for slidably supporting said bracket for adjustment in elevation while 50 holding said cutter frame from turning relatively to said bracket and from turning relatively to said supporting frame, means for sliding said bracket up and down to 55 adjust the elevation of said kerf-cutter and means for operating said kerf-cutter at its various elevations including rectilinear movement of said supporting frame to 60 secure rectilinear feeding movement of said kerf-cutter along a path extending transversely of said kerf-cutter.

50. In a mining machine, the combination 65 with a supporting frame, of upright slide-ways at the forward portion of said frame, spaced-apart elongated chain kerf-cutters each comprising an elongated cutter frame

extending transversely of the forward portion of said supporting frame, a bracket connected rigidly to one of said cutter frames and guided along the upper slideway, an additional bracket rigidly connected to the other cutter frame and guided along the lower slideway, said brackets being connected to said slideways to guide said chain kerf-cutters to various elevations while being held in planes parallel to each other and while being confined against any swinging movement relatively to the supporting frame, means for adjusting said brackets to move the chain cutters toward and from one another while maintaining them in substantial parallelism, and means for operating said chain kerf-cutters in their various adjusted positions.

51. In a mining machine, the combination 70 with a supporting frame comprising an upright guard plate provided with an upright slideway at its forward end, of laterally extending cutter frames connected to said slideway, chain cutters carried by said cutter frames, means for operating said chain 75 cutters at various positions of said cutter frames along said slideway, a motor for driving said operating means, and means for supporting said motor and said operating means on that side of said guard plate opposite the location of material cut by said 80 chain cutters.

52. In combination, a mining machine 85 frame, a guard plate carried by said frame, a cutter chain supported on said guard plate, means for driving said cutter chain positioned adjacent said guard plate to be 90 protected thereby, a second guard plate carried on said mining machine frame and spaced from said first-named guard plate 95 to form a chute, a second cutter chain mounted on said second guard plate, and means for driving said second cutter chain positioned adjacent said second guard plate to 100 be protected thereby.

53. In combination, a mining machine 105 frame, a guard plate having the forward end positioned adjacent one edge of said frame, a cutter chain having its forward run positioned adjacent the forward end of 110 said guard plate, a second guard plate carried by said mining machine frame, cutter chains positioned adjacent the forward end of said second guard plate and positioned in planes intersecting the plane of said first 115 mentioned cutter chain, and means for operating said cutter chains arranged in positions relative to said guard plates to be 120 protected thereby from the material severed by said cutter chains.

54. In combination, a mining machine 125 frame, an upright cutter chain for severing a section of material from a mine wall along one side of said section, separate cutter chains for severing said material from 130

the portions above and below said section, horizontally extending arms for supporting said last named cutter chains, means for adjusting said arms vertically, and adjustable means for driving said cutter arms at the various positions of said arms.

55. In a mining machine, the combination with a supporting frame, of a chain kerf-cutter mounted on said frame in position for cutting a kerf in an approximately horizontal plane, an additional chain kerf-cutter mounted on said frame in position for cutting a kerf in an upright plane, said additional kerf-cutter having a run adjacent to the inner end of the horizontal kerf-cutter, said horizontal kerf-cutter comprising a cutter frame having relatively movable sections, and means for adjusting said sections toward and from each other.

56. In a mining machine, the combination with a supporting frame, of an upright kerf cutter mounted on said frame to extend longitudinally thereof relative to the path of travel of said frame, an undercutting kerf cutter mounted on the forward end of said frame in position to extend transversely thereof to cut an under kerf approximately meeting the lower edge of the upright kerf, and adjustable means for varying the length of the under cutting kerf cutter to adjust the proximity between the same and said upright kerf cutter.

57. In a mining machine, the combination with a supporting frame, of an upright plane-kerf cutter mounted thereon in position to cut an upright kerf, a horizontal kerf cutter mounted on said frame to extend transversely thereof to a position adjacent said upright kerf cutter in position to cut a horizontal kerf intersecting the upright kerf cut by said upright kerf cutter, means for operating said kerf cutters to cut such intersecting kerfs, and adjusting mechanism to extend the horizontal kerf cutter to various positions to adjust the proximity of said horizontal kerf cutter to said upright kerf cutter.

58. In a mining machine, the combination with a supporting frame, of an upright slideway carried by said frame, spaced-apart laterally extending horizontal kerf-cutters each comprising a cutter frame adjustable along said slideway, an upright kerf-cutter mounted on said frame to span the space between the inner ends of said spaced-apart kerf-cutters, means for driving said spaced-apart kerf-cutters at the various positions of their cutter frames along said upright slideway, and means carried by the inner end portions of said spaced-apart kerf-cutters to adjust their lengths relatively to said upright kerf-cutter to cause said spaced-apart kerf-cutter and said upright kerf-cutter to cut communicating kerfs.

59. In a mining machine, the combination with a supporting frame, of an upright guarding device mounted on said frame, an upright slideway at the forward end of said guarding device, spaced-apart chain kerf-cutters each comprising a sectional cutter frame, means for adjusting said cutter frames vertically along said slideway and for holding said cutter frames in adjusted positions, means for adjusting the relative positions of the sections of each chain kerf-cutter to vary its length and its reach relatively to the inner edge of said supporting frame, means for operating said chain cutters at the various positions of said cutter frames along said slideway, a motor for driving said chain cutter and operating means, and means for supporting said motor and said operating means adjacent said guarding device for protection against dislodged material.

60. In a mining machine, the combination with a supporting frame, of a chain-cutter comprising a cutter frame extending across one end of said frame and connected thereto so as to be confined against swinging movement during operation thereof including feed, means for operating said under-cutting chain kerf-cutter to cut a kerf in advance of one end of said frame, said operating means comprising means for moving said frame and chain-cutter rectilinearly along a path extending transversely of said chain kerf-cutter, and an upright guard mounted on said frame in position to protect said operating means against dislodged material by directing such dislodged material away from such operating means.

61. In a mining and loading machine, the combination with a conveyor comprising an elongated frame adapted to rest on the floor of a mine chamber parallel to a mine wall and spaced therefrom, said conveyor comprising a traveling element having superimposed portions traveling in opposite directions, of means for operating said conveyor, means for anchoring the frame of said conveyor to hold such frame stationary, and means for dislodging material from the mine wall and automatically directing it onto said conveyor while the frame of the latter remains anchored and acts as a lateral abutment for the dislodging means during the travel of the latter along said conveyor.

62. In a mining and loading machine, the combination of an elongated traveling conveyor comprising an elongated conveyor frame, of means for anchoring said frame spaced a predetermined distance from a mine wall, and mechanism for cutting material from the mine wall and directing it onto said conveyor while said conveyor frame acts as a lateral abutment therefor to confine the feeding movement of said cut-

ting mechanism along a predetermined path.

63. In a mining and loading machine, the combination with a main frame, of an endless traveling conveyer mounted on said main frame, a core-cutting mining machine comprising chain kerf-cutting mechanism with an unobstructed core-opening extending therethrough, means for guiding said core-cutting mining machine along said main frame intermediate the ends thereof and along an unobstructed space between said main frame and an upright mine wall, means for directing dislodged material from said unobstructed core-opening of said core-cutting mining machine onto said conveyer, and means for operating said conveyer to convey dislodged material toward loading position while such mining machine occupies various positions intermediate the ends of said conveyer.

64. In a mining and loading machine, the combination with a conveyor comprising a frame, of means for anchoring said frame to hold it stationary, means for operating said conveyor, a mining machine comprising core-cutting mechanism and a frame adapted to slide along said conveyor frame while the latter acts as a lateral abutment during the operation of said core-cutting mechanism, means for operating said mining machine including movement thereof along the space between the conveyor frame and the working face while said conveyor frame acts as a lateral abutment as aforesaid, and means for directing cut material from the mine vein to said conveyor at the various positions of the mining machine along said conveyor.

65. In a mining machine, the combination with a supporting frame, of an upright kerf-cutter and two spaced-apart transverse kerf-cutters in position to cooperate with said upright cutter to cut a single column of material along a mine wall, means for operating said kerf-cutters including rectilinear feed of said supporting frame and movement thereof under the column of material, a deflector mounted on said frame in position for engaging the rear end of said column of material to break it and deflect it from the outer edge of said frame, and means for vibrating said deflector to assist in breaking the column of material and effecting the transfer of the broken material from said edge.

66. In a mining machine, the combination with a supporting frame, of an upright kerf-cutter extending along the inner edge of said frame to the forward end thereof, means for operating said kerf-cutter including rectilinear feed of said frame substantially parallel to the plane of said upright kerf-cutter, a deflector on said supporting frame back of a space adjacent said upright

kerf-cutter and unobstructed over substantially the entire height of said upright cutter, and mechanism for vibrating said deflector to assist said deflector in effecting the transfer of cut material from said unobstructed space toward loading position.

67. In a mining machine, a frame, an upright cutter chain mounted at one edge of said frame for severing a section of material from a mine wall, horizontally extending cutter chains for forming a kerf above and below said section of material, a deflector for moving the material so severed away from said mine wall, and mechanism for vibrating said deflector to assist in said moving operation.

68. In a mining machine for severing a continuous section of material from a mine wall, a cutter arranged to form a loop through which said section of material passes as said machine is moved along said wall, and a door for closing the open portion of said loop.

69. In a mining machine, the combination with a supporting frame, of a plurality of chain kerf-cutters mounted on said frame to form a loop having an unobstructed core-opening therethrough, means for operating said chain kerf-cutters to cut a core section extending through said loop during the forward movement of the machine, and a door movable into position to prevent cut material from falling forward through such loop when the machine is being moved from the end of a cut into position for beginning another cut.

70. In combination, a mining machine having a base plate, of a cutter carried by said machine in position to form a substantially continuous loop at one side thereof, means for moving said machine along the face of a mine wall to sever a section of material from said wall and to cause said section to move through said loop onto said base plate, and a door for closing said loop to prevent the escape of material therethrough when said machine is being moved into position to make a second cut.

71. In mining apparatus, a mining machine having a laterally extending cutter forming a loop at one side thereof, means for moving said machine along the face of a mine vein to cause said cutter to sever a section of material from said vein, and a ram for forcing material severed by said cutter from said machine when said machine has reached the end of a cut.

72. In combination, a mining machine having a base plate, a cutter positioned above said base plate and arranged to form a laterally extending loop at one side of said machine, means for moving said machine along the face of a mine vein to cause said machine to sever a section of material from said vein, deflectors carried by said machine

for moving said material therefrom as said machine is moved along said vein, and a ram for pushing the material remaining on said machine therefrom when said machine 5 reaches the end of a cut.

73. In a mining machine, the combination with a supporting frame, of a plurality of plane kerf-cutters each comprising a flat cutter frame and an endless cutter chain 10 mounted thereon, means for supporting said plane kerf-cutters on said frame in position to cut a single core of material along the upright face of a mine wall, and means for operating said kerf-cutters including the 15 driving of the said individual cutter chain and the rectilinear feed of said supporting frame to effect the cutting of a substantially continuous kerf in the form of a loop extending inwardly from the face of the mine 20 vein.

74. In a mining machine, the combination with a supporting frame, of two individual spaced-apart plane kerf-cutters mounted on said frame with a free and unobstructed 25 core space between them and in position for cutting spaced-apart kerfs in substantially horizontal parallel spaced-apart planes, an upright individual kerf-cutter mounted on said frame in position to cut an upright kerf 30 connecting the inner ends of said spaced-apart horizontal kerfs and having its upper and lower limits respectively adjacent the inner ends of said horizontal kerf-cutters, and means for operating said kerf-cutters 35 to effect the cutting of a single core extending through the free and unobstructed opening between said horizontal cutters and in front of said upright cutter.

75. In a mining machine, the combination 40 with a supporting frame, of a plurality of individual plane kerf-cutters mounted on said frame with their forward cutting edges in substantially the same upright plane extending transversely of the mine wall, said 45 individual kerf-cutters being also mounted on said frame in position to form a loop having an unobstructed core opening there- 50 through, and means for operating said plane kerf-cutters to cut a single core along the mine wall by cutting spaced-apart kerfs ex- 55 tending into the mine wall at different elevations and by cutting an upright connecting kerf spaced back from the face of the mine wall.

76. In a mining machine, the combination 55 with a supporting frame, of horizontally ar- 60 ranged kerf-cutters separately mounted on said frame in spaced-apart relation, an up- 65 right kerf-cutter mounted on said frame, means for operating said kerf-cutters each to cut a kerf only in its own plane, and mechanism for supporting said kerf-cutters to confine the forward cutting edges thereof to substantially the same upright plane.

77. In a mining machine, the combination

with a supporting frame, of individual elon- 70 gated horizontal spaced-apart kerf-cutters carried at the front portion of said frame and extending transversely of the path of feeding travel thereof each in position to cut a plane kerf spaced from the other kerf cutter, and an individual upright kerf-cutter separately mounted on said frame and hav- 75 ing its forward cutting portion arranged in substantially the same transverse plane as the cutting portions of said horizontal kerf-cutters.

78. A long wall mining machine comprising a supporting frame, a plurality of in- 80 dividual spaced-apart horizontally arranged kerf-cutters each extending across the for- 85 ward end of said supporting frame and each in position to cut only in its own plane, an upright kerf-cutter carried by said frame in position to cooperate with said horizontal kerf-cutters to cut a core of material along the mine wall, and means for supporting said kerf-cutters by permanently confining the forward cutting portions thereof to sub- 90 stantially the same plane extending trans- 95 versely of the path of feeding travel of the machine.

79. In a mining machine, the combina- 95 tion with a supporting frame, of an upright plane kerf-cutter comprising an endless cutter chain mounted on said supporting frame in position to form an upright kerf-cutter offset inwardly from the face of the mine 100 vein, said kerf-cutter having its forward upright cutting portion permanently ar- 105 ranged substantially in the same transverse plane as that extending through the forward portion of said supporting frame, and means for operating said plane kerf-cutter including rectilinear movement of said sup- 110 porting frame along said face to secure feeding movement of said kerf-cutter recti- 115 linearly in its upright plane to cut a kerf the lower limit of which is approximately in the plane of the floor of the mine cham- 120 ber.

80. In a mining machine, the combina- 115 tion with a supporting frame, of an up- 120 right kerf-cutter, means for supporting said upright kerf-cutter on said frame in position to cut an upright kerf offset in- 125 wardly from the face of the mine vein with its lower limit approximately in the plane of the floor of the mine chamber, a hori- 130 zontally arranged plane kerf-cutter sepa- 135 rate from said first-named kerf-cutter, means for supporting the horizontal kerf- 140 cutter on said frame in position to form a horizontal kerf extending inwardly from the face of said mine vein to connect with the kerf formed by said upright kerf-cutter, said individual upright kerf-cutter and said individual horizontal kerf-cutter being per- 145 manently arranged with their forward cut- 150 ting portions in substantially the same 150

plane extending transversely of the path of travel of said supporting frame and approximately at the forward end thereof, and means for operating said kerf-cutters including rectilinear movement of said supporting frame to secure feeding movement of said kerf-cutters to cut individual kerfs in intersecting planes, the lower limit of the upright kerf being approximately in the plane of the floor of the mine chamber and the inner limit of the horizontal kerf connecting with the upright kerf while the forward cutting portions of said kerf-cutters remain permanently in such upright transverse planes.

81. In a mining machine, the combination with a supporting frame, of an upright kerf-cutter carried by said frame at one side thereof in position to form a kerf offset inwardly from the face of a mine vein, a pair of horizontally arranged individual cutters carried by said frame in position to form plane kerfs extending inwardly from the face of said vein to the kerf formed by said upright kerf-cutter, said kerf-cutters each operating only in its own plane, in fixed relative relation with their cutting portions permanently in substantially the same plane at the forward end of said supporting frame with the lower limit of the upright kerf-cutter approximately in the plane of the floor of the mine chamber, and means for operating said kerf-cutters including movement of said supporting frame along the face of the mine vein to secure feeding movement while said individual cutters remain in such fixed relative relation with their cutting portions in such transverse planes.

82. In a mining machine, the combination with a supporting frame, of a plurality of individual chain kerf-cutters mounted at the forward end of said frame in position to form a substantially continuous kerf extending inwardly in the form of a loop from the face of the upright mine wall, said chain cutters being mounted in fixed relation to each other and to said supporting frame with their cutting portions permanently positioned in substantially the same transverse plane at the forward portion of said supporting frame, each of said chain cutters cutting in its own plane only and the lower limit of the cutting being substantially in the plane of the floor of the mine chamber, and means for operating said kerf-cutters including rectilinear movement of said supporting frame to secure feeding movement of said kerf-cutters while the latter remain in such fixed relation to each other and to said supporting frame.

83. In combination, a mining machine frame, chain cutters positioned at one end of said frame and arranged with their cut-

ting ends in adjacent planes to sever a core of material from a mine wall along the lateral faces of said core, and a deflector carried by said frame for breaking said core transversely thereof.

84. In a mining machine, the combination with a supporting frame, of cutting mechanism forming the loop positioned at the forward end of said frame with the cutting lengths in approximately the same upright transverse plane for cutting a single core of material from a mine vein, and a deflector carried by said frame in position for breaking said single core transversely thereof.

85. In a mining machine, the combination with a supporting frame, of an upright chain kerf-cutter extending along the forward inner edge of said frame with a forward upright cutting edge approximately in the plane extending transversely through the forward end of said frame, means for operating said upright kerf-cutter to cut a kerf offset inwardly from the face of a mine vein, and a deflector mounted on said frame in position to extend from the forward inner edge of said frame intermediate the longitudinal ends of said upright kerf-cutter to the rear outer edge of said frame.

86. In a mining machine, the combination with a supporting frame, of an upright kerf-cutter carried by said frame and extending along the inner forward edge thereof, spaced-apart horizontal kerf-cutters at the forward end of said frame in position to cooperate with said upright kerf-cutter to cut a core of material along the mine wall, a base plate carried by said supporting frame and extending to a scooping position substantially in the plane of the lower horizontal kerf-cutter, said lower horizontal kerf-cutter and said scooping edge of said base plate being mounted on said supporting frame to occupy a position substantially at the floor of the mine chamber, and a deflector extending from the inner forward edge of said supporting frame intermediate the longitudinal ends of said upright kerf-cutter to the outer edge of said supporting frame.

87. In a mining machine, the combination with a supporting frame, of an upright cutter carried by said frame at one side thereof and arranged to form a kerf offset inwardly from the face of the mine wall with the lower limit of the kerf approximately in the plane of the floor of the mine chamber, separate horizontally arranged cutters for forming kerfs extending inwardly from the face of the mine wall to the upright kerf in position to form a single core of material, the forward cutting edges of said separate kerf-cutters and of said upright kerf-cutter being arranged in substantially the same

- transverse upright plane at the forward end of said frame, and a deflector carried by said frame in position to engage the single core of material and break the same transversely thereof. 65
88. In a mining machine, the combination with spaced apart chain kerf cutters each having a flat cutter bar, of an intermediate chain kerf cutter having a flat cutter bar spaced back from the face of a mine wall, and means of operating said kerf cutters to cut a U-shaped kerf entering the mine wall at spaced apart positions. 70
89. In combination, a mining machine frame, a plurality of chain cutters operating in intersecting planes for severing material from the face of a mine vein, means for moving said frame and cutter along the face of said vein, and a deflector arranged to direct the material severed by said cutter away from its native position and beyond the path of movement of said frame. 75
90. In a mining machine, the combination with a supporting frame, of an upright plane chain kerf-cutter mounted on the inner side of said frame and extending beyond the forward end thereof, means for effecting rectilinear feed of said cutter by rectilinear movement of said frame along the mine wall in a direction parallel to the upright plane of said kerf-cutter to cause said kerf-cutter to cut a kerf between two previously cut spaced-apart kerfs, a curved chute mounted on said frame and comprising a curved deflector in position to direct the cut material off the outer side of said frame, and means back of such deflector for actuating said kerf-cutter during the said rectilinear feed thereof. 80
91. In a mining machine, the combination with a supporting frame, of kerf-cutting mechanism mounted on said frame and extending transversely of the forward end thereof, means for actuating said kerf-cutting mechanism mounted on the forward outer side of said supporting frame, and a chute on said supporting frame extending back from said kerf-cutting mechanism and comprising an upright wall adjacent said actuating means in position to protect the same against dislodged material. 85
92. In a mining machine, the combination with a supporting frame, of kerf-cutting mechanism comprising spaced-apart horizontal kerf-cutters extending transversely across the forward end of said frame in position to cut parallel spaced-apart kerfs, means mounted on the forward end of said frame for operating said kerf-cutting mechanism, and a chute extending rearwardly from said cutting mechanism along said supporting frame, said chute comprising an upright wall on said frame adjacent said operating means in position to protect the latter by preventing movement of dislodged material against the same. 90
93. In a system of mining, the combination with a supporting frame, of cutting mechanism carried by said frame and movable bodily therewith, of means for operating said cutting mechanism including rectilinear travel of said supporting frame along the face of the mine wall, a conveyer closely adjacent the path of travel of said frame in position for receiving dislodged material from said frame throughout the path of travel of said cutting mechanism and said frame, and a deflector mounted on said frame in position to automatically effect the transfer of cut material from the mine wall over said frame directly onto said conveyer. 95
94. In a system of mining, the combination with a movable supporting frame, of cutting mechanism carried by said frame and movable bodily therewith, means for operating said cutting mechanism including rectilinear feeding movement of said frame along the face of the mine wall, a stationary frame located adjacent the path of travel of said movable frame on that side thereof remote from the mine wall, a conveyer mounted on said stationary frame in position to have a path of travel closely adjacent the path of travel of said movable frame, an upright curved chute for effecting the transfer of cut material over said movable frame directly onto said traveling conveyer, and means for operating said conveyer to transport the material as fast as dislodged and in the direction of feeding movement of said movable frame. 100
95. In mining apparatus, the combination with a movable supporting frame, of a stationary supporting frame closely adjacent the path of travel of said movable frame and substantially parallel to such path of travel, cutting mechanism mounted on said movable frame and movable bodily therewith, means for operating said cutting mechanism, including feed thereof by bodily movement of said movable supporting frame, an endless conveyer mounted on said stationary frame and having superposed portions traveling in opposite directions closely adjacent the path of travel of that side of said movable frame remote from the mine wall, and a curved chute mounted on said movable frame for effecting the transfer of cut material directly from said movable frame onto said conveyer from that side of said movable frame closely adjacent said stationary frame. 105
96. In a system of mining, the combination with a movable supporting frame, of cutting mechanism carried by said frame at one end portion thereof, means for actuating said cutting mechanism, means for moving said frame along the face of the

- mine wall to effect feeding movement of said cutting mechanism, a conveyer extending along the face of the mine wall in a position spaced back therefrom closely adjacent the path of travel of said frame, means for driving said conveyer to transport dislodged material in the direction of movement of said frame and said cutting mechanism, and a deflector connected to said frame to move therewith to direct severed material from the rear portion of said frame beyond the path of movement thereof and directly onto said conveyer.
97. In a mining machine, the combination with a supporting frame, of spaced-apart plane kerf-cutters, each comprising an elongated frame and an endless chain-cutter traveling around the same, a guide frame connected between said elongated frames, means for adjusting the positions of said elongated frames along said guide frame relatively to said supporting frame to effect adjustments of said kerf-cutting mechanism relative to said supporting frame, and means for operating said kerf-cutting mechanism including the feed thereof to cut parallel spaced-apart kerfs in a mine wall simultaneously.
98. In a mining machine, the combination with a plurality of spaced-apart plane kerf-cutters, of a guide frame for supporting said kerf-cutters in spaced-apart parallel planes each substantially at right angles to the length of said guide frame, perforated lugs extending from said guide frame, means co-acting with said lugs for adjusting the positions of said kerf-cutters relative to said frame, and means for operating said kerf-cutters.
99. In a mining machine, the combination with a supporting frame, of an under-cutting kerf-cutter mounted on the forward end of said supporting frame, an upright kerf-cutter positioned at the inner edge of said supporting frame with the space above said under-cutter adjacent said upright cutter free and unobstructed over the entire height of said upright cutter above said under-cutter, and a deflector carried by said frame for directing the material severed by said cutters from said unobstructed space and away from the unmined mass.
100. In a mining machine, the combination with a supporting frame having a forward receiving edge adapted to enter an under-kerf approximately in the plane of the mine floor, of a cutter for forming a kerf into which said receiving edge may be moved, an upright guard plate carried by said supporting frame, an upright kerf-cutter supported by said guard plate in position to form a kerf spaced back from the face of the mine wall, and means for operating said upright kerf-cutter, said operating means being located in position to be protected by said guard plate.
101. In a mining machine, the combination with a supporting frame, of a plurality of plane kerf-cutters positioned at one end of said frame and arranged with their cutting edges in adjacent upright planes extending transversely of the forward end of said frame to sever a core of material from a mine wall, and a chute mounted on said frame for directing the cut material laterally from said frame.
102. In a mining machine, the combination with a supporting frame, of a plurality of kerf-cutters each comprising an endless cutter chain and a flat cutter bar, means for mounting said plurality of kerf-cutters at the forward end of said frame in position to cause the cutting paths of travel of the respective cutter chains to be approximately in the same plane extending transversely of the forward end of said frame, the cutter bars of said kerf-cutters being mounted on said frame to have a free and unobstructed core-opening through the space adjacent said cutter bars, means for operating said kerf-cutters to cut a single core of material extending through such unobstructed core-opening of said cutting mechanism, and a chute mounted on said supporting frame in position for directing the core of material laterally from said frame.
103. In a mining machine, the combination with a supporting frame, of three plane kerf-cutters mounted on said frame, one in position to cut an upright kerf and the other two in spaced-apart positions to cut horizontal kerfs extending to the upper and lower limits of said upright kerf-cutter to provide an unobstructed core-opening between the spaced horizontal kerf-cutters and in front of the upright kerf-cutter for the passage of a single core of material cut by said cutters, means for driving said kerf-cutters, means for moving said frame and cutters rectilinearly along the face of the mine wall to secure rectilinear feeding movement of said cutters, and means mounted on said frame for directing the material severed by said cutters away from its native position and beyond the path of movement of said frame.
104. In a mining and loading system, the combination with a supporting frame, of core-cutting mechanism mounted at the forward end of said frame with its cutting edges in adjacent upright transverse planes, means mounted on said frame for actuating said core-cutting mechanism, means for effecting rectilinear movement of said frame to secure feeding movement of said core-cutting mechanism during the actuation thereof to cut a single core extending backwardly from said core-cutting mechanism over said frame, a

conveyer adjacent the path of travel of said supporting frame, and means mounted on said supporting frame for continuously directing severed material from said frame 5 onto said conveyer.

105. In a system of mining, the combination with a supporting frame, of kerf-cutting mechanism mounted thereon for cutting a single core of material along a mine wall 10 to project from said kerf-cutting mechanism onto said frame, means for operating said kerf-cutting mechanism including rectilinear feed of said frame, a conveyer extending along the path of travel of said frame, and 15 a curved chute mounted on said frame for directing the cut material from said kerf-cutting mechanism continuously onto said conveyer during the rectilinear feeding travel of said frame and said kerf-cutting 20 mechanism.

106. In a system of mining, the combination with a supporting frame, of core-cutting mechanism mounted on the forward end of said frame to form a loop having an unobstructed core-opening therethrough, means 25 for operating said core-cutting mechanism to cut a single core of material extending through such unobstructed core-opening, a conveyer adjacent the path of travel of said frame, and means mounted on said frame for transferring the cut material directly 30 onto said conveyer.

107. In a system of mining, the combination with an elongated conveyer spaced back 35 from the upright face of the mine wall but extending along the same, of a mining machine located between said conveyer and the mine wall to have a path of travel closely adjacent said conveyer, means for moving 40 said mining machine along such path of travel to secure the feed thereof, and means on said mining machine for effecting the transfer of severed material continuously directly onto said conveyer during the operation 45 of the latter and during the feeding movement of such mining machine.

108. In a mining machine, the combination with a supporting frame, of an elongated chain kerf-cutter comprising a flat cutter bar extending across the forward end of 50 said frame in position to cut a substantially horizontal kerf along the mine wall, means for confining said cutter bar against turning movements relatively to said frame, means 55 for actuating said chain kerf-cutter, means for effecting rectilinear movement of said supporting frame to secure rectilinear feeding movement of said chain-cutter in a direction extending transversely thereof, and 60 means for adjusting the elevation of said chain kerf-cutter relatively to said frame without interfering with said confining means.

109. In a mining machine, the combination 65 with a supporting frame, of an upright

guideway rigidly connected thereto, an upright bracket connected to said cutter frame and mounted in said guideway to hold said cutter frame permanently against swinging movement relatively to said supporting frame and to hold said cutter frame in position extending permanently transversely of said supporting frame at one end thereof to afford an unobstructed space for the passage of cut material past said kerf-cutter onto 70 said supporting frame, and means for adjusting the elevation of said bracket to vary the elevation of said kerf-cutter.

110. In a mining machine, the combination with a supporting frame, of upright guideway mechanism rigidly connected to said supporting frame at the forward end thereof, spaced-apart elongated kerf-cutters associated with said guideway mechanism and extending across the forward end of said supporting frame in spaced-apart relation with an unobstructed opening between the same for the passage of cut material past 80 said kerf-cutters onto said supporting frame, and means for adjusting the elevation of each 85 of said transverse elongated kerf-cutters.

111. In a mining machine, the combination with a supporting frame, of upright guideway mechanism rigidly mounted on said supporting frame at the forward end thereof, spaced-apart elongated chain kerf-cutters associated with said guideway mechanism and extending across the forward end of said supporting frame and in advance thereof, one of said kerf-cutters being adapted to 90 occupy a position at the floor of the mine chamber and the other at the roof thereof with an unobstructed space between them for the passage of cut material onto 95 said supporting frame, means for adjusting the elevation of the floor kerf-cutter, additional means for independently adjusting the elevation of the roof kerf-cutter, means for actuating said chain kerf-cutters simultaneously at the various elevations to which adjusted; and means for effecting rectilinear 100 movement of said supporting frame to secure feeding movement of said kerf-cutters in a direction transversely thereof.

112. In a mining machine, the combination with a supporting frame having a forward receiving edge, of an upright kerf-cutter mounted on said frame, of a pair of spaced-apart kerf-cutters mounted on said frame to cut spaced-apart kerfs extending to 115 the upper and lower limits of said upright kerf-cutter to form an unobstructed core space adjacent said kerf-cutters for the passage of a single core of material onto 120 said frame over said receiving edge, means for driving said kerf-cutters, and means for moving said supporting frame to effect rectilinear feed of said cutting mechanism.

113. In a mining machine, the combination 125 with a supporting frame having a for-

ward receiving edge extending to the floor of a mine chamber and across one end of said frame, three plane kerf-cutters mounted on the forward end of said frame one being 5 an upright kerf-cutter and the other two horizontal kerf-cutters in position to cut kerfs extending to the upper and lower limits of said upright kerf-cutter and in position to form with the upright kerf-cutter an unobstructed core spaced for the 10 passage of a single core of material between the horizontal kerf-cutters and adjacent the upright kerf-cutter and over said receiving edge onto said frame, and means 15 for operating said kerf-cutters including rectilinear movement of said supporting frame to secure feeding movement of said kerf-cutters and the movement of the forward receiving edge of said frame under 20 the core material.

114. In mining apparatus, a conveyer arranged to be positioned along the face of a mine vein to be worked, severing mechanism movable along said conveyer and the 25 face of said vein for severing material from said vein and directing said material onto said conveyer, means for moving said conveyer to carry the material placed thereon in the same direction in which said severing 30 mechanism is moved to sever material, means arranged to be positioned in an entry at the side of the section of said vein being worked, toward which said severing mechanism is moved in making a cut, for receiving the material from said conveyer, and means for adjusting said severing mechanism to permit said mechanism to be positioned in an entry at the other side of the 35 section of said vein being worked.

115. In mining apparatus, a conveyer arranged to be positioned along the face of a mine vein, severing mechanism movable along said conveyer and the face of said vein for severing material from said vein 45 and directing it onto said conveyer and also movable into position opposite an entry at one side of the section of said vein being worked, means for receiving material from said conveyer and connected with the 50 discharge end thereof and arranged to be positioned in an entry at the side of the section of said vein being worked opposite to the entry previously mentioned, a mechanism for moving said conveyer, severing 55 mechanism, and receiving means relative to the face of the vein to be worked.

116. A mining machine comprising a frame having a core-receiving end, a curved deflector chute for directing material transversely of said frame after being received by said receiving end, and a scoop at the forward lower portion of said frame between the receiving end and the discharge end thereof.

117. A mining machine comprising a

frame having a platform extending to a core-receiving end, an upright curved deflector chute extending from said receiving end to the discharge end of said frame, and a scoop between the receiving and discharge 70 ends of said frame.

118. In a mining machine, the combination with a core-cutter having an unobstructed core-opening therethrough, of means for operating said core-cutter, a 75 stationary conveyer frame extending along the mine wall, an endless conveyer on said frame, means for operating said conveyer, a deflector for directing pieces of said core onto said conveyer at the various positions 80 of said core-cutter along said conveyer, and means for guiding said core-cutter and said deflector along said stationary frame.

119. In a mining machine, the combination with a rectangular core-cutter, of means 85 for actuating the same to cut a flat roof and a flat floor, a frame for carrying said core-cutter and said actuating means, means for guiding said frame along a mine wall, and mechanism comprising a rope drum and 90 a rope thereon having its free end anchored in the mine for effecting the feed of said core-cutter along the mine wall.

120. In a mining machine, the combination with a core-cutter, of a core deflector, 95 means for operating said core-cutter, a frame for guiding said core-cutter and said deflector along a mine wall during the actuation of said core-cutter, and means comprising a pair of rope drums and a pair 100 of ropes connected to the ends of said guiding means for shifting said core-cutter and deflector to a new initial cutting position in a direction substantially at right angles to the line of feeding movement.

121. In a mining and loading machine, the combination with core-cutting mechanism, of means for operating the same including the feed thereof, a guide frame for said core-cutting mechanism, a conveyer mounted 110 on said guide frame, a deflector following said core-cutting mechanism, means for retracting said core-cutting mechanism toward initial position, means for operating said conveyer, and means for shifting said 115 core-cutter, deflector, frame and conveyer to a new starting position.

122. In a mining and loading machine, the combination with a core-cutter, of means for operating the same including the feed 120 thereof, a conveyer having a stationary frame, a deflector following said core-cutter and acting to move the dislodged material onto said conveyer, and a device extending through said core-cutter to effect movement 125 of the dislodged material onto said deflector at the end of the feeding movement of said core-cutter.

123. In a system of mining, the combination with a mining machine frame, of kerf- 130

cutting mechanism mounted thereon, means for operating said kerf-cutting mechanism including rectilinear movement of said mining machine frame to effect the feeding 5 of said cutting mechanism along a mine wall, an elongated conveyer comprising a conveyer frame, an endless conveyer extending longitudinally thereof to occupy a position adjacent the path of travel of said 10 mining machine frame and substantially parallel to such path of travel in position to receive material from the mining machine throughout the feeding path of travel thereof, and means on said mining machine frame 15 for directing the dislodged material from said mining machine onto said endless conveyer as said mining machine travels along the side of said conveyer.

124. In a system of mining, the combination 20 with a mining machine frame, of kerf-cutting mechanism extending in advance of said frame relatively to the feeding path of travel thereof in position to cut spaced-apart horizontal kerfs and an upright connecting 25 kerf spaced back from the face of the mine wall, each of said kerfs being in advance of said frame, means for operating said kerf-cutting mechanism including rectilinear feed of said frame along the face of a mine 30 wall to cut a column of material extending onto said frame, a conveyer having a stationary frame occupying a position adjacent the path of travel of said mining machine frame, said conveyer also comprising an 35 endless conveyer on said conveyer frame in position to travel parallel to the path of travel of said mining machine frame, and means on said mining machine frame for deflecting cut material onto said endless conveyer continuously during the feeding movement of said kerf-cutting mechanism.

125. A mining and loading machine comprising an elongated main frame adapted to be located substantially parallel to the working 45 face of a mine wall and spaced a short distance therefrom, of a core-cutting mining machine comprising kerf-cutting mechanism extending around an unobstructed core-opening, means for guiding the core-cutting mining machine along said frame while extending laterally therefrom across the space between said frame and said mine wall, means for feeding said mining machine along said frame, mechanism for deflecting 50 the core material away from the mine wall, and an endless traveling conveyer extending along said frame in position to continuously receive pieces of core material extending through said unobstructed core-opening 55 during the operation of said mining machine.

126. A mining and loading machine comprising an elongated main frame adapted to occupy a stationary position parallel to the 60 face of a mine wall, of an endless traveling

conveyer mounted on said frame, a supplemental frame connected to said main frame for guidance along the same, core-cutting mechanism having an unobstructed core-opening therethrough and mounted on said 70 supplemental frame in position to cut a single core of material along said mine wall, means for operating said core-cutting mechanism including feeding movement of said supplemental frame along said main frame, and means for directing pieces of the single core of material from the mine wall onto said endless traveling conveyer.

127. In a system of mining, the combination 75 with an elongated endless conveyor comprising an elongated conveyor frame, of anchored abutment mechanism for supporting said conveyor and adapted to act as a lateral abutment, a mining machine comprising kerf-cutting mechanism and a supporting frame movable in the space between said conveyor and the working face, means for moving the mining machine along such space to secure feeding movement of said kerf-cutting mechanism while said mining 80 machine is confined to said space by said anchored abutment mechanism, means for directing dislodged material onto said conveyor during feed of said cutting mechanism, and means for continually operating 85 said conveyor during the feed of said mining machine.

128. In a mining machine, the combination 90 with core-cutting mechanism having an unobstructed core-opening therethrough, of means for operating said core-cutting mechanism including feed thereof along the mine wall working face, an elongated endless conveyer spaced a short distance from said mine 95 wall working face, the space between said conveyer and said working face being free and unobstructed for movement of said core-cutting mechanism, means movable with said core-cutting mechanism for gradually and continuously moving portions of the cut core 100 onto said conveyer, and means for operating said conveyer in the direction of feeding movement of said core-cutting mechanism 105 for transferring the dislodged material toward loading position.

129. In a mining machine, the combination 110 with an elongated frame spaced back a short distance from the face of a mine wall and substantially parallel thereto while occupying a stationary position, of an endless conveyer mounted on said frame, a mining machine adapted to travel along the floor of the mine chamber between said frame and said mine wall, automatic means for operating said mining machine including feed 115 thereof along the space between said frame and said mine wall, means movable with said mining machine for directing dislodged material onto said conveyer, and means for operating said conveyer in substantially the 120

125

130

same direction as the feeding path of travel of said mining machine.

130. A mining and loading machine comprising an elongated main frame adapted to be located substantially parallel to the working face of a mine wall and spaced a short distance therefrom, of a core-cutting mining machine comprising kerf-cutting mechanism extending around an unobstructed core-opening, means for guiding the core-cutting mining machine along said frame while extending laterally therefrom across the space between said frame and said mine wall, means for feeding said mining machine along said frame, mechanism for deflecting the core material away from the mine wall, and an endless traveling conveyer extending along said frame in position to continuously receive pieces of core material extending through said unobstructed core-opening during the operating of said mining machine.

131. A mining and loading machine comprising an elongated main frame adapted to occupy a stationary position parallel to the face of a mine wall, of an endless traveling conveyer mounted on said frame, a supplemental frame connected to said main frame for guidance along the same, core-cutting mechanism having an unobstructed core-opening therethrough and mounted on said supplemental frame in position to cut a single core of material along said mine wall, means for operating said core-cutting mechanism including feeding movement of said supplemental frame along said main frame, and means for directing pieces of the single core of material from the mine wall onto said endless traveling conveyer.

132. In a mining machine, a loop cutter, means for maintaining the cutting plane of said cutter in an upright position, a receiving table arranged in the rear of said cutter to receive material severed thereby, and a ram for removing the material from said table.

133. In a mining machine, the combination with core-cutting mechanism having an unobstructed core-opening therethrough, of means for operating the same including feeding movement bodily along a mine wall, apparatus movable with said core-cutting mechanism for dislodging the core, and means arranged along the path of travel of said core-cutting mechanism and said dislodging mechanism in position for receiving material from the latter and transferring the same in the direction of feeding movement toward loading position.

134. In a mining and loading machine, the combination with a main frame, of a conveyer mounted thereon, loop chain core-cutting mechanism guided along said main frame and having a continuous cutting stroke around the core from the place where the cutting mechanism enters the mine wall

to the place where it emerges therefrom, a curved chute in position to direct the cut core of material onto said conveyer, and means for moving said core-cutting mechanism along said main frame.

135. In a mining and loading machine, the combination with a stationary frame, of a conveyer thereon, a supplemental frame movable longitudinally of said main frame, core-cutting mechanism mounted on said supplemental frame and comprising chain kerf-cutting means having an unobstructed core-opening therethrough, means for operating said core-cutting mechanism to cut a core parallel to said stationary frame, means for directing dislodged material from said unobstructed core-opening onto said conveyer, and means for moving the main frame and supplemental frame together with the parts mounted thereon, to a new initial position preparatory for another cut across the mine wall.

136. In a system of mining, the combination with a conveyer having a stationary frame, of core-cutting mechanism for cutting a core of material parallel to said conveyer, means for directing dislodged material onto said conveyer at various positions of said core-cutting apparatus along said conveyer, and rope gearing for moving said conveyer and said core-cutting apparatus to a new initial position.

137. A mining and loading machine comprising an elongated main frame adapted to be located substantially parallel to the working face of a mine wall and spaced therefrom, of a supplemental frame guided along said main frame, core-cutting mechanism having an unobstructed core-opening therethrough and mounted on said supplemental frame to extend laterally therefrom across the space between said main frame and said mine wall, means for moving said supplemental frame along said main frame to effect feeding movement of said core-cutting mechanism, mechanism for deflecting the core material away from the mine wall, and an endless traveling conveyer extending along said main frame in position to continuously receive pieces of core material during the operation of the core-cutting mechanism.

138. In a mining machine, the combination with a supporting frame, of an angular supplemental frame having an upright leg and a horizontal leg, an upright guide on the frame into which said upright leg is adapted to slide vertically, a plane kerf-cutter mounted on the horizontal leg of said supplemental frame to occupy a plane extending in a general horizontal direction, means for operating said kerf-cutter to produce a flat kerf in a single plane in an upright mine wall adjacent said frame, and manually operated mechanism connected be-

- tween said guide and the upright leg of said supplemental frame for adjusting the position of said kerf-cutter by moving said supplemental frame up and down relatively to said guide into varying parallel positions.
139. In a mining machine, the combination with a supporting frame, of a vertical guide thereon, a right angle bracket having a vertical arm connected to said guide for up and down rectilinear sliding movement relatively thereto, a kerf-cutter mounted on the horizontal arm of said bracket and confined to a single predetermined horizontal plane of movement, means for operating said kerf-cutter to produce an individual flat kerf in a mine wall in a plane at right angles to the path of movement of said bracket, and means connected between said guide and the vertical arm of said bracket for rectilinearly adjusting the elevation of the latter to effect movement of said kerf-cutter transversely of its plane into horizontal planes parallel to each other.
140. In a mining machine, the combination with an individual roof kerf-cutter for cutting a separate flat kerf in a single plane, of a floor kerf-cutter for cutting a flat kerf in a single plane, of means for operating said kerf-cutters, and manually operated mechanism for moving said kerf-cutters toward and away from each other to adjust the distance between the same.
141. In a mining machine, the combination with a supporting frame, of spaced-apart individual chain kerf-cutters mounted on said supporting frame, means for confining the feeding movements of said kerf-cutters to predetermined parallel planes, means for adjusting the position of each individual kerf-cutter relatively to said frame to adjust the distances between said kerf-cutters while maintaining them in parallelism, and means for operating said kerf-cutters including feeding movements thereof in their adjusted positions and in parallel planes.
142. In a mining machine, the combination with a main frame, of two supplemental frames, one extending upwardly from said main frame and the other extending downwardly therefrom, a chain kerf-cutter mounted on the upper supplemental frame, an additional chain kerf-cutter suspended from the lower supplemental frame, means for adjusting the positions of said supplemental frames together with the kerf-cutters mounted thereon to vary the distance between said kerf-cutters, and means for operating said kerf-cutters while in any of their adjusted positions to cut spaced-apart kerfs in a mine wall simultaneously.
143. A mining machine comprising a frame, an upright curved chute deflector for directing material transversely of said frame, and a scoop connected to said frame for directing material into said chute.
- In testimony whereof I have signed my name to this specification, on this 25th day of March A. D. 1916.
- EDMUND C. MORGAN.
